UNITED STATES PATENT OFFICE

LYMAN C. HUFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS FOR TREATING PETROLEUM OIL

Original application filed May 17, 1922, Serial No. 561,585. Divided and this application filed May 7, 1925, Serial No. 28,539. Renewed February 18, 1929.

This invention relates to improvements in a process for treating petroleum oils, and refers more particularly to a process for the conversion of relatively heavy oils into lighter oils such as gasoline and the like.

This application is a division of an application filed by me May 17, 1922, Serial No. 561,585.

Among the objects of the invention are to provide a process in which the oil is heated to a conversion temperature in a heating zone and is passed to a vaporizing stage in which the lighter portions are separated out and pass off in vaporous form, the heavier liquid being drawn off as residual material.

A further object of the invention is to provide an improved method of heating the oil and in the arrangement of the apparatus used therefor.

The single figure is a diagrammatic side elevational view of the apparatus with parts and section.

Referring to the drawing, the oil to be treated is introduced from any convenient extraneous source through the line 1 controlled by the valve 2 and is passed through the upper layer of tubes 3 positioned near the top of the tube compartment 4 of the furnace 5. The furnace 5 comprises a combustion chamber 6 in which the burners 7 are situated and the tube compartment 4 in which the heating coils are positioned. The gases of combustion pass from the chamber 6 through the ducts 8 downwardly through the compartment 4 passing off to stack through the flue 9.

The oil after being subjected to the hottest combustion gases entering the tube compartment from the combustion chamber, passes down through the line 10 through which it is introduced to one of the lower tubes 11 of the bank of tubes which are positioned in the tube compartment. The oil introduced to the lower tube flows successively through the continuous coil working its way upwardly from the cooler portion of the tube compartment toward the hottest portion which is the top. By the time it has reached the upper tubes, its temperature has been raised sufficiently to cause a conversion of the oil, at which time it is

passed through the transfer line 12 which is connected to the vaporizing chamber 13. The transfer line terminates in a pipe 14 which extends well into the center of the vaporizing chamber in the form of a spout, the end 55 of which is turned downwardly to introduce the vaporous fluid oil into the central part of the vaporizing chamber, thus preventing any collection of carbon about the transfer line at the point at which it enters 60 the chamber.

The vaporizing chamber preferably comprises a vertical cylindrical chamber mounted within insulated walls 15. At the top is a clean-out manhole 16 and a similar manhole 17 situated at the side. The lower portion of the chamber is preferably conical, a residuum line 18 controlled by valve 19 being situated at the apex of the cone for drawing off the heavier unvaporized oil. An emergency residual drawoff line 20 controlled by valve 21 is inserted into the side of the chamber to draw off the residual substance should the lower line become clogged or obstructed.

The insulation about the vaporizing chamber consists of materials such as an inside layer of fire felt, an intermediate layer of sponge felt with an outer casing of steel plate. An insulating wall of this character not only serves to more effectively retain the heat of the chamber but absorbs much less of the heat from the process than does a brick or masonry insulating wall.

Near the lower part of the evaporating chamber in the sides of the insulating walls are situated air dampers 22 and similar dampers 23 near the top of the chamber. By manipulating these dampers the cooling air permitted to circulate about the chamber may be controlled and the temperature of the vaporizing chamber likewise regulated.

The vapors evolved in the chamber, pass off through a line 24 controlled by a valve 25 to the dephlegmator 26 where they are subjected to a refluxing action. After dephlegmation, the still vaporous products pass off from the top of the dephlegmator through the line 27 controlled by the valve 28 to the water condenser coil 29 mounted in condenser box 30. From the condenser coil the

distillate flows through the line 31 regulated by the valve 32 to the receiving tank 33 where the condensed vapors are collected as liquid distillate.

5 The gaseous pressure upon the system is controlled by the relief valve 34 and similar control valves positioned in different portions of the apparatus. The receiver is equipped with a pressure gauge 35, a liquid 10 level gauge 36 and a liquid drawoff valve 37.

The reflux condensate separated out in the dephlegmating chamber is returned through the line 38 controlled by valve 39, and is charged with the incoming raw oil to the line 15 10 where it is subjected with the oil to heat treatment in the heating zone.

When cracking hydrocarbon oil, particularly the more refractory oils, it is often necessary to subject them to temperatures having a very deteriorating effect upon the furnace tubes. This is particularly true where the combustion gases come in direct contact with the heating tubes and with those tubes which contain the hottest oil. By excess 25 heating, the tubes are not only weakened but are pitted and must be continuously replaced if some provision is not made for tempering the heat of the combustion gases that come in contact with the tubes containing the hottest 30 oil.

As a remedy for these difficulties as shown in the drawing, the incoming oil is circulated in an upper layer of tubes which come in contact with the hottest combustion gases 35 coming through the ducts 8 which connect the combustion chamber 6 with the tube chamber 4. Thus the cool oil is subjected to the hottest furnace temperature, and by circulating the cool oil 40 through this layer of tubes 3 the oil charge is considerably heated prior to its introduction to the main bank of tubes positioned just below the upper preheating tubes. Subsequent to the preheating of the oil, it is 45 passed down through line 10 which is heavily insulated, to the lower tubes in the furnace and its travel is then upwardly through the continuous coil until it flows through the tubes just below the upper preheating tubes. 50 At this point the oil is at its highest temperature, but the tubes containing the hottest oil are shielded from the hottest furnace temperatures by the overlying preheating tubes which tend to temper somewhat the excessive 55 heat of the combustion gases. The hot oil after being raised to a conversion temperature passes from the tubes through the transfer line 12 into the vaporizing chamber 13 where a greater part of the conversion takes 60 place. The vapors evolved pass off through the vapor line 24 and after being refluxed and condensed are collected as distillate in the receiver 33. The reflux condensate is returned and recycled with the incoming oil 65 charge.

The temperature of the vaporizing chamber is carefully regulated by the dampers 22 and 23 which control the circulation of air within the circular wall 15. Instead of maintaining the oil at a level in the vaporizing chamber, it is intended that the residuum and heavier unvaporized products be continuously drawn off so as to prevent the collection and accumulation of carbonaceous matter in the bottom of the chamber. Where 70 the oil is maintained at a level in the chamber the carbon collects on the side walls beneath the oil level while above the oil level in the vapor space there is very little collection of carbonaceous material. Thus by continuously drawing off the liquid oil and precipitated carbon which is contained therein in a suspended state, the period of operation is considerably lengthened as the process will 75 not have to be slowed down for cleaning.

In the event of an accumulation of carbon in the lower conical portion of the vaporizing chamber, an alternate emergency line is inserted as shown at 20. The conical form of the chamber also assists in the flushing out 80 of the carbon and preventing the accumulation of precipitated carbon particles along the side of the walls of the chamber.

The process may be operated continuously and under a substantial pressure of the generated vapors.

By treating mid-continent gas oil of approximately 32° Baumé to temperatures ranging from 700° to 900° F., and pressures of from 50 to 200 pounds, a substantial yield 90 of from 30 to 50% high grade distillate having a Baumé gravity of from 48° to 52° may be obtained.

It has been found that the vapors in the reaction chamber of a cracking system have 105 a tendency to stratify, the lighter ones going to the top, and the heavier ones collecting near the bottom of the chamber. By locating the discharge from the heating tubes in the bottom of the vaporizing stage, the fluid 110 oil which is introduced thereto separates, the vapors therefrom rising through the stratified zone of gaseous vapors, and the residual liquid substance being drawn off from the bottom of the chamber. The passage of the 115 vapors through the stratified area has a tendency to separate the lighter and heavier vapors conforming with the zones of the stratified area.

By regulating the circulation of air about 120 the chamber, the condensation of the vapors in the chamber is controlled. The condensate produced therein flowing down the sides of the chamber will carry with it any precipitated carbon which has a tendency to collect or adhere to the side of the chamber. The liquid residue and carbon containing condensate is drawn off to prevent any accumulation of liquid in the bottom of the 125 chamber.

I claim as my invention:

1. A process for cracking hydrocarbon oil consisting in raising the oil to a conversion temperature in a heating zone, passing the heated fluid oil into an elongated vertical vaporizing stage where substantial separation of lighter fractions in the form of vapors takes place, permitting the vapors to have an unobstructed upward travel through the vertical vaporizing stage, preventing the accumulation of precipitated carbon by flushing down the walls of the vaporizing stage with condensate produced by circulation of cool air about the vaporizing stage, preventing substantial accumulation of liquid residue in the vaporizing stage and maintaining a regulated vapor pressure during treatment. 80
2. A process for cracking hydrocarbon oil consisting in raising the oil to a conversion temperature in a heating zone, passing the heated fluid oil to an elongated vertical vaporizing stage and there introducing it near the bottom thereof where substantial vaporization takes place, permitting the vapors to have a substantially unobstructed passage upwardly through the vertical vaporizing stage, preventing the accumulation of precipitated carbon by flushing down the walls of the vaporizing stage with condensate produced by circulation of cool air about the vaporizing stage, preventing substantial liquid residue accumulation in the vaporizing stage, drawing off and condensing the vapors rising to the top of the vaporizing stage, and maintaining regulated pressure upon the oil during treatment. 85
3. In processes for cracking hydrocarbon oil of the character in which the oil is subjected to a cracking temperature while advancing through a heating zone and thence transferred to an enlarged reaction chamber from which vapors and liquid oil are separately removed, the improvement which comprises introducing the heated hydrocarbons from the heating zone into the reaction chamber approximately in line with the vertical axis thereof to prevent carbon accumulation in the reaction chamber at the point of introduction of hot oil thereto, and circulating a cooling medium about the walls of the reaction chamber to flush down the walls of the reaction chamber with condensate formed by such cooling. 90
4. A process of heating petroleum oils in tubular coils situated in a furnace which comprises first passing the oil through the part of the coil located in the hottest zone of the furnace, concurrent with the passage of combustion gases in said furnace, then passing the oil directly through a portion of the coil situated in the coolest zone of the furnace, and removing the oil from the coil at a point located at the point intermediate the hottest and coolest point of the furnace. 100
5. A process for continuously heating 105
- petroleum oil which comprises first passing the oil through a coil at the point of maximum heat of the furnace, passing the oil concurrently with the flow of combustion gases in the furnace, then passing the oil through a portion of the coil situated in a relatively cooler zone of the furnace, passing the oil counter-current to the flow of combustion gases and removing the oil from the coil at a point intermediate the hottest and coolest 75 zone of the furnace. 110
